UNITED STATES PATENT OFFICE

2,361,180

FIREARM

Jósef Dobřemysl, Cambridge, England

Application February 28, 1941; Serial No. 381,097
In Great Britain November 17, 1939

1 Claim. (Cl. 89—1)

This invention relates to firearms.

One object of the invention is to provide for easy dismantling of guns without the necessity of placing damaged parts on the ground and to operate guns also in prostrate position of the gunner.

Another object of the invention is to provide means for easy and quick opening of the rear part of the gun and tilting this part out of the path of the breech mechanism when removing the latter from the gun.

A further object of the invention is to provide means for preventing the rear part of the gun to be tilted until it has been drawn into its rearmost position.

Another object of the invention is to provide means rendering the gun body sturdy and resisting to bending stresses and deformations in operation of the gun.

A still further object of the invention is to provide improved means for elastically absorbing the shocks to which the gun or its parts are subjected in operation or handling.

According to the invention the trigger housing with the shoulder piece are made as one unit which with its associated parts is arranged for longitudinal sliding movement along the casing of the gun and after releasing a suitable locking device it can be drawn back and in its retracted position tilted down and the shoulder piece set on the ground, so that in combination with the support or bipod it may be used to support the gun with the breech in the open position clear of the ground. The breech mechanism which is slidably mounted, can then be drawn back so as to be freely accessible for inspection, adjustment or exchange of parts. When the cause of failure has been removed the mechanism can be pushed forward to its normal position and the rear part of the fire arm, after being raised about its pivot, can be pushed forward and secured in position by the locking device.

Other objects, features and advantages will appear from the drawings and the description hereinafter given.

One way of carrying out the invention is shown in the accompanying drawings, wherein

Fig. 1 is a side view of the rear part of the gun in its normal position,

Fig. 2 is a side view, partly in section, showing how the gun is supported for the purpose of removing the mechanism,

Fig. 2a is a side view, partly in section, show-

ing the mechanism of the gun removed from the casing of the gun.

Fig. 3 represents a side view of a part of the gun adjacent of the trigger housing with the rear part partly drawn back in the direction of the arrow A.

Fig. 4 is a similar view of the part of the gun as illustrated in Fig. 3 but with the rear part swung down.

Fig. 5 is a cross-section of the gun taken on the line 5—5 of Fig. 3 showing a detail of the gun in its open position.

Fig. 6 is a cross section taken on the line 6—6 of Fig. 7 on a larger scale illustrating the guide 15 for the sliding rear part of the gun.

Fig. 7 is a sectional view of the buffer device of the gun.

The gun, shown by way of example in the drawings, comprises a gun casing 1 connected with the barrel 2. The breech mechanism may be of any design and in the present example a breech mechanism of the tilting breech block type is shown. It consists substantially of a breech block 3, breech block carrier 4 and recoil spring 5. These parts are shown in Fig. 2 in their working position and in Fig. 2a in a retracted position removed from the gun casing. The gun may be arranged for any type of feeding and in the drawing feeding from a magazine 6 is shown. The operation of a breech mechanism of this kind is well known and need not be described in detail.

A trigger mechanism 7 is arranged in a trigger housing 8. The trigger mechanism itself may be of any design and does not form part of the present invention. A guide 9 for the recoil spring 5 is mounted in the trigger housing. At the rear end of the trigger housing 8 a shoulder piece 10 is secured, preferably by bolts or in any other way. The shoulder piece forms thus one unit with the trigger housing. A longitudinal slot 11 is provided in the trigger housing for the passage of a locking bolt 12 which serves to fasten the trigger housing in its operative position on the casing of the gun. The purpose of the longitudinal slot 11 will be explained hereinafter.

Suitable guiding means are provided on the casing 1 of the gun and on the trigger housing 8 for allowing longitudinal movement of the trigger housing along the casing 1. In a preferred embodiment of the invention a so called cross guide is used for this purpose. Fig. 4 shows a guide of this type in cross section. The wall of the casing 1 is provided at one side with a rib 13 extending in the direction of the sliding move-

ment. The other part of the guide on the trigger housing 8 is formed to embrace with its sections 14 and 15 both the wall of the casing 1 and its rib 13. In this way the gun casing is reinforced against bending stresses and deformation of its side walls and any lateral movement or yielding of the rear part of the gun, especially during firing operation and handling is positively avoided.

A pivot 16 is arranged at the front end of the trigger housing 8 (see Figs. 3 and 4). The pivot 16 has flattened parts 17 adapted for engagement with corresponding guiding slots 18 formed in the bearing 22 for the pivot 16. The bearing 22 is connected or made integral with the casing 1.

The rear part of the trigger housing 8 comprises a spring buffer 19 with a spring 20, see Fig. 5. When in operative position, the buffer abuts against projections 21 on the casing 1. The buffer is further shaped so as to co-act with 20 the rear face of the breech block carrier 4.

The spring buffer serves three purposes:

First, it absorbs the recoil shock of the barrel 2. The barrel 2 is connected with the casing 1 so that the recoil shock of the barrel is transmitted to the casing 1 and by the intermediary of the projections 21 to the buffer and spring 20.

Second: being made to cooperate with the rear surface of the carrier 4 the buffer is capable to absorb that part of the recoil shock of the carrier and the mechanism associated with it, which was not absorbed by the recoil spring 5.

Third: The buffer 10 and spring 20 allow the shoulder piece 10 to yield upon an impact on the latter. In order to allow this movement the slot 11 for the locking bolt 12 is made longitudinal (Figs. 2 and 5).

To open the gun the locking member, such as the bolt 12, securing the trigger housing with 40 its associated parts to the casing of the gun, is

released and the trigger housing 8 with the shoulder piece 10, the trigger mechanism 7, the recoil spring 5, its guide 9 and the buffer and spring arrangement 19, 20, may be drawn back until the pivot 16 passes the slot 18 and enters its bearing, and then turned downwardly around the pivot 16 and the shoulder piece 10 set on the ground. The gun supported at its front end by a support or bipod 22 rests now at its rear end 10 on the shoulder piece as an additional support or leg. The breech mechanism can be then drawn back, as shown in Fig. 2a. The fire arm is assembled in reverse sequence of operations.

The flattened parts 17 and the corresponding guiding parts 18 on the casing prevent a turning of the trigger housing after it slides free of the casing ribs 13 and until it has been drawn to its fully retracted position.

I claim:

In a fire arm a barrel, a firing casing, a support for the fire arm at its front part, a recoiling breech block mechanism, a housing enclosing a trigger mechanism, a shoulder piece arranged immediately behind said firing casing, said shoulder piece forming a downwardly tiltable unit with said trigger housing to serve as a second support, guiding means in said firing casing and on said trigger housing permitting limited longitudinal movement for securing the trigger housing in position on said casing, a pivot pin in the trigger housing on which the rear part of the fire arm is swung, a bearing for said pivot pin arranged on said firing casing, guides for the pivot pin in said bearings, said pivot pin having flattened parts adapted for engagement with said guides on said bearing in the last stage of the backward movement of the rear part of the fire arm and guiding it after it has come out of engagement with the guiding means in the casing of the fire arm.

JOSEF DOBŘEMÝSL.
